UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,496, dated September 27, 1881.

Application filed August 9, 1881. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

Series of leaves and flowers of peculiar zig-

zag outline are arranged on the background of the carpet and joined by stems into one continuous design, having a resemblance to a collection of thistle-leaves, flowers, and stems. The ornaments A B C D E are themselves of harmonious and striking outline.

I claim—

The design for carpets, substantially as shown.

WINTHROP L. JACOBS.
